UNITED STATES PATENT OFFICE.

PAUL F. SHIVERS, OF WABASH, AND GARLAND W. OBENCHAIN, OF FORT WAYNE,
INDIANA.

FLEXIBLE AND FOLDING TABLE.

Application filed February 23, 1921. Serial No. 447,306.

To all whom it may concern:

Be it known that we, PAUL F. SHIVERS, residing at Wabash, in the county of Wabash and State of Indiana, and GARLAND W. OBENCHAIN, residing at Fort Wayne, in the county of Allen and State of Indiana, citizens of the United States, have invented new and useful Improvements in Flexible and Folding Tables, of which the following is a specification.

The invention relates to flexible and folding tables and particularly to tables adapted to be used by chiropractors in the treatment of their patients.

It is desirable in many cases that the central portion of a table used by chiropractors and others who treat persons for ailments by manipulation of the organs, muscles and nerves of the body and by adjusting the bones of the body, shall be flexible in its central portion so that the portion of the patient's body resting thereon shall not be rigidly supported, and it is also desirable that the table shall be capable of being folded up into a comparatively small package for easy transportation by the user. The object of the invention is to provide a simple, durable table of few parts which shall contain the above advantages among others.

One embodiment of the invention is illustrated in the accompanying drawings, in which—

Figure 1 is a side elevational view of the table fully extended; Fig. 2 an end view of the same, the devices connecting the central flexible portions of the top being omitted; Fig. 3 a plan view of the lower side of one half of the top of the table; Fig. 4 an end view of the central flexible portions; Fig. 5 an enlarged side view of the pivoted central support and Fig. 6 an end view of the same partially in section.

Referring to the drawings, the table consists of a top made preferably in four sections 10, 11, 12 and 13, sections 10 and 11 being hinged together by hinges 14 and sections 12 and 13 hinged together by hinges 15. The two end sections 10 and 13 are preferably supported on four legs 16, 17, 18, 19. The upper ends of legs 16 and 19 are laterally recessed to permit of the insertion of latches 20 which are pivoted to the bottom of sections 10 and 13 respectively, the engagement of the latches with the legs serving to lock the top sections to the legs. The

other legs 17 and 18 merely abut the lower side of the sections 10 and 13. If desirable recesses may be provided in the lower side of sections 10 and 13 into which the upper ends of the legs will project when the top sections are placed upon them. The legs are connected together by the foldable or collapsible frames 21, 22, 23 which connect the legs longitudinally relatively to the table and by a similar frame 24 between each pair of legs which extends transversely relatively to the table. The bars of each frame are pivoted together the ends of each frame being pivoted to collars 25 and 26 on the legs, collars 25 being movable on the legs and collars 26 being fixed thereon. When the top sections are removed from the legs, the latter are readily collapsed as a unit into an exceedingly small space, by simply forcing one end pair toward and to the other. The upward movement of collars 25 on the legs, produced by forcing one pair of legs toward the next, draws the legs of each pair together, so that by the time the legs on one side are close together the legs on the other side will also be close together and close to those on the former side, making a compact bundle which is easily carried about.

To each frame 22 is pivoted a support or bar 27 the upper end of which will abut the lower surface of one or both intermediate sections 11, 12 of the top and rigidly support them when it is desirable to do so. The lower end of each support 27 is bent to abut the side of one of the bars, as 28, which bar forms part of the frame and to which the support is pivoted. The abutting faces of support 27 and bar 28, near the end of support 27, are provided with a knob 29 and recess 30 respectively, which, when in engagement, lock the support in the upright position, the lock being easily broken or separated by rotating the support on its pivot 31.

When supports 27 are not desired they are rotated downwardly and the two sections 11 and 12 are held up in the following manner:

Plates 32, 33 are hinged to sections 11 and 12 respectively and depend therefrom. Springs 34 are removably connected to both plates. Rod 35 is connected at its upper end to section 12 and its lower end is hook-shaped and engages the lower edge of plate 33. A cable 36 is connected to the lower end of plate 32 its other end being connected to

the shaft 37 of a windlass 38 which is mounted on section 11. By winding up the windlass, with rod 35 in engagement with plate 33, plate 32 is drawn away from plate 33 thereby placing upon springs 34 the desired tension. The two sections 11 and 12 are now capable of being depressed on their hinges, the springs furnishing a resistance to that movement according to the tension placed upon them.

Since the plates 32, 33 are hinged to plates 11 and 12 and rod 35 is also separable from plate 33 and the springs are removable from one or both plates, the sections, when the 15 top is removed from the legs, may be folded respectively against the lower side of the end sections with the plates between them. The two folded sections may then be easily carried or inserted in a suitable case along 20 with the collapsed legs for transportation.

Numerous modifications in details of construction will be suggested to one skilled in the art, hence we do not wish to be limited to the precise constructions and arrangement 25 of parts above described.

What we claim is:

1. A table consisting of a plurality of

legs collapsibly secured together, a plurality of top sections removably supported by the legs, intermediate sections movably supported on the other sections, means connected to the intermediate sections for holding them in tension and means to vary the tension of the same.

2. A table consisting of a plurality of 35 legs, collapsible frames connecting the legs, a plurality of top sections supported by the legs, intermediate top sections hinged to the former top sections, means connected to the intermediate sections for holding them in 40 tension, and means pivotally mounted on the collapsible frame to rigidly support the intermediate sections.

3. A table consisting of a two part top, means to support the top, the adjacent ends 45 of the two parts being flexible, resilient means having a flexible connection to each flexible end and means to adjust the tension of the resilient means for the purposes described.

In witness whereof we have hereunto signed our names.

PAUL F. SHIVERS.
GARLAND W. OBENCHAIN.
